SPEED-REGULATING MECHANISM FOR
WIRE WINDING AND LIKE MACHINES

Samuel Hugh Richards, Harpenden, England

Application January 5, 1934, Serial No. 705,369
In Great Britain January 5, 1933

1 Claim. (Cl. 242—25)

This invention relates to wire drawing, wire winding, tinsel spinning, wire enamelling and like machines in which wire or the like has to be wound in layers on a spool.

5 The object of the invention is to provide an improved speed-regulating mechanism for such machines whereby the speed of rotation of the spool may be adjusted to a suitable new value as each succeeding layer is added to the winding thereon in order to ensure a constant speed of absorption 10 of the wire or other product being wound and a constant tension therein.

According to this invention the spool winding the wire or the like is driven by an infinitely variable speed gear and the means oscillating a guide arm serving to direct the wire to the spool is arranged to adjust the ratio of the infinitely variable gear step by step in such manner as to reduce slightly the rate of rotation of the spool 20 as each new layer is commenced.

25 The form of infinitely variable speed gear employed is preferably that comprising two oppositely coned pulleys coupled by an endless belt adapted to be displaced longitudinally of the pulleys by means of a belt fork in order to vary the ratio of the gear.

In the preferred construction of the speed-regulating apparatus according to this invention the belt fork of such a variable speed gear 30 is adapted to be displaced by means of a nut and lead screw combination, the lead screw being rotated in the appropriate direction, step by step, by means comprising a clutch device permitting of the amount of said rotation being varied to suit the thickness or diameter of the wire or the like being wound.

The application of the invention to a wire drawing machine will now be described in order that the nature thereof may be readily understood, reference being made to the accompanying drawings wherein:—

Figure 1 is an end elevation of a wire-drawing machine,

Fig. 2 is a front elevation thereof,

Fig. 3 is a fragmentary detail view, to a larger scale,

Fig. 4 is plan view, partly in section, of the elements shown in Fig. 3,

Fig. 5 is a diagrammatic front elevation of a detail in one position of the parts, and

Fig. 6 is a similar view in another position of the parts.

Figs. 7 and 8 are views similar to Figs. 3 and 4 showing a modified construction.

55 The wire winding pool 1 is mounted on a shaft

2 driven by an endless belt 3 running over two oppositely coned pulleys 4 and 5, belt 3 being guided by a fork constituted by a jockey pulley 6 carried by a nut 7 mounted on a lead screw 8 having a quick pitch thread. The lead screw 8 is rotatably mounted in a suitable manner so that it extends parallel with the axes of the coned pulleys 4 and 5 and has secured thereon at a suitable point in its length, preferably on an unthreaded end thereof, a concentric wheel 9 (Figs. 3 to 6) which is surrounded by an eccentrically disposed laterally extending internal cam rim or flange 10a formed on a second wheel 10 which is secured to one end of a sleeve 10b loosely mounted on an unthreaded portion of the said screw 8.

In the space between the outer periphery of the concentrically mounted wheel 9 and the inner periphery or cam surface of the eccentrically disposed rim or flange 10a there is disposed a roller 11 which is rotatable freely between two laterally extending lugs 12 carried by an arm 13 extending radially from a bearing boss 13a by which it is loosely mounted on the lead screw 8. The roller 11 is of such diameter 20 that its periphery is adapted to contact with the surfaces of both the outer periphery of the concentric wheel 9 and the inner periphery or cam surface of the eccentric rim 10a at a point substantially midway between that at which the space between said surfaces is widest and that at which said space is narrowest, and the normal setting of the parts is that in which the roller 11 is so in contact with the arm 13 carrying same is inclined upwardly somewhat from the horizontal 25 and the widest part of the said space is disposed substantially vertically above the lead screw 8 (see Fig. 6).

At its outer or free end, which extends beyond the laterally extending lugs 12 confining the roller 11, the said arm 13 may be suitably weighted at 13' (Figs. 3, 4, 5 and 6) if its own weight should require this augmentation, the weight preferably being adjustable along the arm, and a stop 14, adjustable by means of the screw 40 45 15 and lock-nut 16, is provided to co-act with the arm in limiting the downward movement thereof under the action of the weight.

On the sleeve 10b of the wheel 10 formed with the eccentric rim or flange 10a above referred to there is secured adjustably, as by a split band 17 drawn tight by a bolt 18, a radially projecting arm 19 engaging the upper end of a push-rod 20, the lower end of which is articulated to the one arm 21 of a two-armed lever 21, 22. 50 55

The other arm 22 of said lever carries a roller 23 adapted to run in a cam groove 24 having a snail-cam formation with two steps disposed 180° apart, said cam groove being formed in the end face of a barrel cam 25 employed to oscillate the guide arm 26 (Figs. 1 and 2) relatively to the spool 1 winding the wire leaving the final wire-drawing pulley 27, in order to layer the wire on said spool.

10 The angular disposition of the steps of the snail-cam groove 24 relatively to the cam 25 oscillating the guide arm 26 is such that the roller 23 co-acting with the snail-cam groove 24 has always reached the crest of a rise in the latter just as the guide arm 26 is approaching the one or other end of its travel.

15 During the depression of the roller 23 by a rise on the snail-cam groove 24, the wheel 10 carrying the eccentrically disposed rim 10a is rotated freely about the lead screw 8 in such a direction (counterclockwise from the position shown in Fig. 6) that the widest part of the space between the inner periphery of the said rim 10a and the outer periphery of the wheel 9 secured on the lead 20 screw 8, is displaced downwardly (Fig. 5) from its normal position (Fig. 6), which latter view corresponds to the said roller bearing on the lowest point of a rise on the cam, with the result that the heavy or weighted arm 13 swings downwardly 25 until it is arrested by the stop 14 above referred to, the roller 11 being carried with said arm due to the provision of the lugs 12.

20 Now as the guide arm 26 reaches the end of its travel the roller 23 running in the snail-cam groove leaves the crest of the rise which depressed it and rises comparatively rapidly, whereby the eccentric rim 10a is rotated back to its normal position. During this movement of the rim, however, it tightly wedges or cams the roller 11 carried by the arm 13 against the outer periphery of the concentric wheel 9 on the lead screw 8 so that a rotational movement is imparted to said wheel and thus to the lead screw 8 itself. Adjustment may be effected to allow more or less 30 idle turning of the rim 10a before it cams or wedges the roller 11 against the wheel 9 and turns the lead screw 8, and thus the amount which said lead screw is turned, may be infinitely varied within limits. Such adjustment is effected by 35 setting the stop screw 15 to vary the distance which the arm 13 and the roller 11 may descend. When the setting of screw 15 allows roller 11 to descend to the maximum, just as soon as rim 10a starts on its return or retrograde movement (from position of Fig. 5 toward that of Fig. 6), the screw 8 will be turned, and such turning will 40 continue until said rim 10a reaches the limit of said return movement. However, when screw 15 is set to allow less descent of roller 11, the rim 45 10a will, of course, have idle movement before it causes said roller to turn the lead screw.

45 As will be understood, the rotation of the lead screw 8 thus produced advances the nut 7 thereon a predetermined distance longitudinally thereof, whereby the driving belt 3 is moved to a new position along the oppositely coned pulleys 4 and 5 and the speed of rotation of the spool 1 is correspondingly reduced for the winding of the next layer of wire thereon.

50 When it is desired to reset the speed-regulating mechanism for winding a fresh spool the lead screw 8 is rotated in the reverse direction to that in which it is fed step by step by means of a hand-wheel or crank 28 secured thereon.

To allow this resetting rotation of the lead screw 8, the arm 13 serving to displace the roller 11 need only be lifted slightly from its normal position and it is preferred to provide a spring retaining catch 29 in such a position that a pin 5 30 projecting laterally from the end of the arm will automatically engage therein (see Fig. 3) when so lifted, thus obviating the necessity for manually retaining the arm in the lifted position.

55 The stroke of the arm 13 may be accurately 10 adjusted to any desired degree of fineness by varying the position of the stop 14 with which it co-operates and the lead screw 8 is preferably made readily detachable so that it may be quickly replaced by another of different pitch when required.

60 Although reference has been made to an eccentrically disposed rim or flange in the above description, the clutch device described may also be constructed with the outer member mounted concentrically with the lead screw, the inner periphery of said member comprising two portions both concentric with the lead screw and of different radii, the adjacent ends of the portions being connected by comparatively short surfaces running eccentrically with respect to the said screw.

65 In this case the axial dimension of the annular gap between the portion of larger radius and the concentric boss on the lead screw would be slightly greater than the diameter of the roller 30 carried by the weighted arm and the corresponding dimension of the annular gap between the portion of smaller radius and the boss would be less than said diameter.

70 Furthermore, although the cam shaft 31 carrying the cams 24, 25 controlling the oscillation of the guide arm 26 and effecting the variation in the speed ratio of the drive to the wire-winding spool 1 may be driven in the usual manner through high-ratio reduction gearing 32, 33, 34, 40 35 from the spool shaft 2, as seen in Figs. 2, 3 and 4, it is preferred to drive the cam shaft 31 through such gearing from a lay shaft 36 (Figs. 7 and 8) which carries a separate coned pulley 37 and is belt-driven at 39 from the coned pulley 5 which 45 drives, through belt 3, the coned pulley 4 on the spool shaft 2.

75 This necessitates two belt forks being provided on the nut 7 actuated by the lead screw 8, the one 6 engaging the belt 3 driving the spool shaft 2 and 50 the other 38 engaging the belt 39 driving the lay shaft 36, so that the speed of the cam shaft 31 may be reduced in accordance with the reduction in the speed of the spool shaft 2.

In this manner the spool shaft is relieved of the 55 varying load due to the operation of the cams, which fact leads to a more uniform speed of rotation of the spool shaft.

I claim:—

80 In a machine of the class described, a shaft provided with a spool upon which to wind wire or the like, said shaft having a cone pulley, a drive shaft parallel with the spool-carrying shaft and also having a cone pulley, a belt trained around said cone pulleys for driving said spool-carrying 65 shaft, a lead screw mounted between and parallel with said shafts, a nut engaged with said lead screw and having means engaging said belt to shift the latter along the cone pulleys when the lead screw is turned, a traveling guide for the 70 material being wound on the spool, means for operating said guide including a cam shaft, a second belt trained around the cone pulley of said drive shaft, a third cone pulley driven by said second belt, means driven by said third cone pulley 75

for driving said cam shaft, means on the aforesaid nut for shifting said second belt along its cooperating pulleys as the first named belt is shifted, a one-way clutch for turning said lead screw in a direction to so shift said belts as to decrease the speeds of said spool-carrying shaft

and said cam shaft, and means actuated by said cam shaft for actuating said clutch to turn said lead screw in said direction each time said cam shaft has effected complete travel of said guide.

SAMUEL HUGH RICHARDS.
